GOLF PUTTER

Robert J. Mader, 1607 Hickory St., Torrance, Calif.

Filed Jan. 21, 1965, Ser. No. 83,510

Term of patent 14 years

(Cl. D34—5)

FIG. 1 is a perspective view of the putter taken from one side thereof, showing my new design,

FIG. 2 is a side elevation view of the putter head taken from the side thereof opposite to that of the view of FIG. 1, and

FIG. 3 is an end elevation view of the putter head. The shaft has been shown fragmentarily from FIGS. 1 and 3 for convenience of illustration.

I claim:

The ornamental design for a golf putter, as shown and described.
